UNITED STATES PATENT OFFICE.

HARRY JOHN LOMB, OF ALLEGHENY, PENNSYLVANIA.

SASH-LOCK.

SPECIFICATION forming part of Letters Patent No. 717,424, dated December 30, 1902.

Application filed July 26, 1902. Serial No. 117,100. (No model.)

To all whom it may concern:

Be it known that I, HARRY JOHN LOMB, a citizen of the United States, residing at Allegheny, in the county of Allegheny and State 5 of Pennsylvania, have invented certain new and useful Improvements in Sash-Locks, of which the following is a specification.

This invention relates to a sash-lock; and the primary object of the same is to provide 10 simple and effective means whereby coöperating sash are locked to each other or released in one operation, and thus overcome the objections and extra mechanism required in devices of this class which first lock one sash 15 and then the other.

A further object of the invention is to conveniently locate the controlling devices for the lock so that they may be readily reached and operated when desired and also to insure 20 a positive securement of the sash when the improved devices are in locked condition and obstruct raising and lowering of the sash from the exterior.

With these and other objects and advantages in view the invention consists in the construction and arrangement of the several parts, which will be more fully hereinafter described and claimed.

In the drawings, Figure 1 is a front elevation of portions of window-sash, showing a part of the frame in section and embodying the features of the invention. Fig. 2 is a partial section and elevation of the sash, the upper rail of the lower sash being shown in 35 section. Fig. 3 is a transverse vertical section through the meeting-rails of the sash and the lock devices, a part of the coöperating elements of the latter being shown in elevation. Fig. 4 is a detail section of a portion 40 of a sash rail and frame, showing a rack-and-pinion mechanism forming part of the invention.

Similar numerals of reference are employed to indicate corresponding parts in the several 45 views.

The numeral 1 designates a lower sash, 2 an upper sash, and 3 the usual frame in which the sash are mounted and provided with beads, as usual, for holding the said sash in proper 50 spaced relation and to guide the same in their vertical movements. To the outer edge of one bead 4, at one side of the frame at a point

above the upper rail of the lower sash when the latter is lowered, a rack 5 is secured and extends from said point upwardly to the top 55 of the frame, the teeth of this rack being projected inwardly. On the side stile 6 of the upper sash, at a point opposite the location of the rack 5, a second similar rack 7 is secured and also has its teeth projected in- 60 wardly. The teeth of the racks 5 and 7 extend inwardly only far enough for practical engagement therewith of movable devices, which will be hereinafter referred to, and avoid the formation of open spaces between 65 the side rails of the sash when moving over each other, or, in other words, to avoid departure from the ordinary sash arrangement.

A bore 8 is constructed in the upper or meeting rail 9 of the lower sash 1 and extends 70 longitudinally through the upper part of said rail, and intersecting this bore adjacent to opposite ends of the rail 9 and at the center of the latter are slots 10, which extend completely through the said rail in a transverse 75 direction. In the bore 8 a shaft 11 is rotatably mounted, and thereon are secured outer pinions 12 and 13 and a central pinion 14, the said pinion rotating in the slots 10. The teeth of these pinions operatively project be- 80 yond the outer and inner faces of the rail 9, and the pinions 12 and 13 are held in continual mesh respectively with the racks 5 and 7, so that when the sash 1 and 2 are raised and lowered the shaft 11 will be correspond- 85 ingly rotated.

On the inner face of the rail 9, approximately at the center, a bracket 15 is secured and has an upper horizontal arm 16, with a rearwardly-projected angular terminal 17. 90 The arm 16 and its terminal stand inwardly from the inner face of the rail 9, and on the angular terminal 17 thereof is rotatably mounted a disk-head 18, formed with a series of radial sockets 19, extending completely 95 therearound. Secured to the rear side of the disk-head 18 is a pinion 20, the said disk-head and pinion unitedly rotating on the terminal 17. The center of the pinion 20 is far enough to one side of the pinion 14 to permit the teeth 100 of the latter to engage the teeth of the said pinion 20, as clearly shown by Figs. 1 and 3, and hence when the disk-head 18 is free to rotate the upward or downward movement of

either sash will actuate the shaft 8 and pinion 14 and rotate the pinion 20 and head 18. It will thus be seen that if the head 18 and pinion 20 are held against rotation it will be impossible to move either sash, and to lock the said head 18 and pinion 20 against movement a vertically-disposed spring-actuated latch-bolt 21 is arranged below the head 18 in a guide-casing 22, secured to the inner face of the rail 9. The upper end 23 of the latch-bolt is reduced to enter the sockets 19 of the head 18, and the lower end of said bolt is provided with an eye 24, to which is attached the upper end of a pull-cord 25, whereby the latch-bolt may be disengaged from the disk-head 18 to permit the sash 1 and 2 to be raised or lowered. When the latch-bolt is released, the spring engaging the same forces the reduced upper end 23 thereof into the nearest or coinciding socket 19 of the disk-head, and the latter and the pinion 20 will be prevented from rotating, and thus also lock the shaft 8 against movement.

By having the rack 5 secured to a part of the window-frame 3 and the rack 7 attached to a part of the upper sash movement of the two sashes will be permitted and the one can be locked to the frame and the upper sash to the lower sash. By having the pull-cord 25 depend to the lower rail of the lower sash the operator may conveniently disengage the latch-bolt from the disk-head and hold said bolt in disengaged position while raising or lowering the lower sash or lowering and elevating the upper sash. The improved lock also prevents movement of the sash from the

exterior of the window in view of the securement of one sash to the other, and the parts of the lock organization may be varied in proportions and dimensions to suit different 40 applications.

Having thus described the invention, what is claimed as new is—

1. In a sash, the combination of a window-frame, sashes movably mounted therein, racks 45 secured respectively to one side of the frame and the upper sash, pinions carried by the upper rail of the lower sash and held in continual engagement with the said racks, and means for controlling the rotation of the said 50 pinions and locking the sashes against movement.

2. In a sash-lock, the combination of a frame having a rack secured to one side thereof, sashes movably mounted in the frame, the 55 upper sash having a rack on one side thereof, a shaft rotatably mounted in the upper portion of the lower sash and having pinions thereon engaging the said racks and also provided with an intermediate pinion, a rotatable 60 disk-head having radial sockets carrying a pinion meshing with the said intermediate pinion, and a spring-actuated latch-bolt to coöperate with the sockets in the disk-head to hold the latter against rotation. 65

In testimony whereof I affix my signature in presence of two witnesses.

HARRY JOHN LOMB.
